DOUBLING AND WINDING MACHINE.

1,076,516.

Specification of Letters Patent.

Patented Oct. 21, 1913.

Application filed October 4, 1912. Serial No. 723,854.

To all whom it may concern:

Be it known that I, JOANNY PAGERIE, a citizen of France, residing at Paterson, in the county of Passaic and State of New Jersey, have invented a certain new and useful Improvement in Doubling and Winding Machines, of which the following is a specification.

The invention relates to machines for doubling, or folding lengthwise, light fabrics of the tulle class, and winding the same in such folded condition upon cards or boards, and is designed especially for the treatment of malines in packaging such material attractively for the trade.

The object of the invention is to provide a machine which will smoothly and rapidly fold and wind the fabric automatically, and also indicate the length of the folded piece wound upon the card.

The invention consists in certain novel features of construction and arrangement by which the above objects are attained, to be hereinafter described and claimed.

The accompanying drawings form a part of this specification and show the invention as it has been carried out in practice.

Figure 1 is a side elevation of the machine, Fig. 2 is a plan view, Fig. 3 is an end elevation, and Fig. 4 a side view of a portion. Fig. 5 is a plan view with the frame and certain other portions omitted, and Fig. 6 is a corresponding vertical section taken on the line 6—6 in Fig. 5.

Similar letters of reference indicate the same parts in all the figures.

The material M is received for treatment rolled full-width upon a bar or core A which is mounted vertically in a suitable stand or holder B having means for adjusting the height of the roll relatively to the machine located adjacent thereto.

C is the table of the machine supported on a frame C¹ and carrying standards D and E in which are mounted transverse rods D¹ D² and E¹ E² mounted one above the other in pairs at the ends of the table C.

F is a similar rod lying between the pairs and extending from one standard D partly across the table parallel with the rods D¹ D², bent to form an angular horizontal projection at F¹ having a rounded end, and thence extends longitudinally of the table as at F² and is again bent into parallelism with the rods E¹ E² and secured to the standard E.

The folder-guide F serves to determine the doubling or folding line of the fabric, the rounded projection F¹ initiating the fold and the portion F² lying in the bight or fold formed by laying together the upper and lower edges of the fabric as it is received from the vertical roll and guiding it thus folded horizontally and parallel with the upper face of the table, with the upper half or wing of the fabric lying in the narrow space between the folder-guide and upper rods D¹ E¹ and the lower half between the same guide and the rods D² E² thus maintaining the fold over a considerable area. The end of the folded strip then passes over a soft-faced supporting roller G and is pressed upon by a heavy pressure roller H to flatten the fold or crease, thence over a second supporting roller J and is acted upon by an extensor-roll K from which it passes directly to the card L upon which it is wound.

Motion is communicated to the machine by a belt N running on a tight and loose pulley N¹ on a short shaft N² carrying a pulley N³. The belt N is shifted by a foot lever N⁴, and a belt N⁵ on the pulley N³ rotates the longitudinal shaft P through the medium of the pulley P¹ thereon. On the shaft P is a worm P² in mesh with a worm-wheel G² on the transverse shaft G¹ of the soft-faced supporting roller G and rotates the latter. On the opposite end of this shaft G¹ is a double pulley G³ carrying two belts J³ L³, the former an open belt running on a pulley J² on the shaft J¹ of the second supporting roller J, and the latter, a cross-belt, running on a pulley L² on a shaft L¹ of the card-holder L⁴.

The supporting rollers G and J with the pressure-roller H and extensor-roll K are mounted in arms C² extending from the table, which also carry the card-holder L⁴. The heavy roller H acts by gravity alone and its shaft H¹ is simply received and guided in deep vertical notches c in the brackets C³ which permit it to rise and sink in creasing the fabric and to be raised or removed in inserting the goods, and the extensor-roll K is carried by a vertically swinging frame K¹ pivoted in links carried by the arms C² so that it may be lifted for the same purpose and exert its pressure by gravity.

The extensor-roll is of the ordinary con-

struction such as generally used in winding thin fabrics and designed to exert a gentle outward tension on the fabric from the mid-length to the margins in the ordinary manner to hold it distended full width while being wound so as to insure a smooth delivery to the card L.

The counting or measuring is effected through a wheel R in frictional contact 10 with the soft face of the roller G and suitable gearing therefrom to an index R¹ moving over the surface of a dial R² and indicates the surface travel of the supporting roller G and consequently the length of the 15 material passing thereover.

The card-holder L⁴ consists of two flat bars one of which is movable with relation to the other at one end, as is usual, and means, not shown, for locking it to such 20 other with the card L firmly clamped between the two. The fixed bar serves as the shaft L¹ and carries the pulley L².

The machine effects a great saving over 25 the slow process of folding and winding by hand, with the additional advantages of lessening the danger of damage due to unequal strains on the delicate fabric, and increasing the uniformity and attractiveness of the finished packages.

30 I claim:—

1. In a machine of the character set forth, a folder-guide having a rounded projection to initiate the fold and arranged to form a longitudinal fold in the fabric, said folder 35 guide being disposed horizontally and having its projection at one end thereof, a supporting roller over which said folded fabric is drawn, a pressure roller above said supporting roller arranged to complete the 40 fold, a winding device for taking up the folded fabric, a second supporting roller and an extensor-roll between said pressure roller and winding device, and means for driving the winding device and said supporting 45 rollers.

2. In a machine of the character set forth, a folder-guide having a rounded projection to initiate the fold and arranged to form a

longitudinal fold in the fabric, said folder 50 guide being disposed horizontally and having its projection at one end thereof, a roller arranged to exert pressure on the folded fabric to complete the fold, a winding device for taking up the folded fabric, and an extensor-roll between said pressure roller 55 and winding device.

3. In a machine of the character set forth, a folder-guide having a rounded projection to initiate the fold and arranged to form a longitudinal fold in the fabric, said folder 60 guide being disposed horizontally and having its projection at one end thereof, a revolving supporting roller over which said folded fabric is drawn, a pressure roller above said supporting roller and arranged 65 to press by gravity upon the folded fabric to complete the fold, a second revolving supporting roller, an extensor-roll arranged to press by gravity upon the folded fabric, and a revolving card-holder adapted to receive 70 a card and wind the folded fabric upon the latter.

4. In a machine of the character set forth, a holder adapted to receive a vertical full-width roll of fabric, a folder-guide located 75 at the approximate midheight of said roll and disposed horizontally relatively thereto, and formed at one end with an angular horizontal projection with a rounded end, said folder-guide arranged to form a longitudinal fold in the fabric as received from said vertical roll and to lie in said fold as the fabric traverses said guide, means for pressing the folded fabric to complete the fold, an extensor-roll for distending the folded 85 fabric, and a winding-device for drawing the fabric from said vertical roll and winding it in the folded condition.

In testimony that I claim the invention above set forth I affix my signature, in 90 presence of two witnesses.

JOANNY PAGERIE.
